UNITED STATES PATENT OFFICE

166,652

SWING JOINT

Doyle C. Warren, Monrovia, Calif., assignor to
 Chiksan Company, Brea, Calif., a corporation
 of California

Application February 10, 1947, Serial No. 136,795

Term of patent 14 years

(Cl. D91—3)

To all whom it may concern:

Be it known that I, Doyle C. Warren, a citizen of the United States, residing in the city of Monrovia, county of Los Angeles and State of California, have invented a new, original, and ornamental Design for a Swing Joint, of which the following is a specification, reference being had to the accompanying drawings, forming a part thereof.

Fig. 1 is a perspective view of a swing joint, showing my new design, showing one side of the bottom and one end thereof, and Fig. 2 is a perspective view of the swing joint showing the said side, the top and the other end, the other side of the joint being substantially like the side shown.

I claim:

The ornamental design for a swing joint, as shown and described.

DOYLE C. WARREN.
